TYPEWRITER ATTACHMENT

Application filed April 19, 1929. Serial No. 356,389.

This invention relates to typewriters and has especial reference to those in which a continuous roll of paper is employed instead of separate sheets as is usually the case.

- 5 The main object of the invention is to so relate the paper roll with the typewriter that the construction and arrangement and operation of the typewriter are not altered or disturbed in any manner.
- 10 A further object is to provide a simple and efficient attachment for the paper roll and so related to the machine and the platen carriage or the platen shift frame in the platen carriage that it can be very easily and quickly applied thereto and detached therefrom when desired.

A further object is to provide such a mechanism in the form of an attachment and in such manner that the paper feed will be even and smooth and the steady relation of the paper with the platen maintained at all times.

A still further object is to provide that the movements of the platen carriage will be normal and that the force or pressure required to move the platen through the intermediary of the shift key will not be increased.

Still another object is to so relate the paper support and the platen carriage that the support can be applied and detached from the machine without disturbing any of the normal and standard parts whatsoever.

Further and more specific objects, features, and advantages will more clearly appear from the detailed description given below taken in connection with the accompanying drawings which form part of the specification, which illustrate one embodiment of the invention, and in which,

40 Fig. 1 is a somewhat diagrammatic side elevation of the invention applied to a typewriter;

Fig. 2 is a plan view thereof;

Fig. 3 is a rear elevation; and,

45 Fig. 4 is a somewhat diagrammatic side

elevation of a modified form of the invention, wherein a number of rolls are used.

The invention generally considered comprises a roll of paper which is supported independently of the movable platen of the typewriter but preferably from the typewriter frame. The roll is mounted on a movable carriage and frictional connections extend from the roll support to the platen carriage or to the platen shift frame in the carriage so that when the platen carriage moves, the roll support moves also in a horizontal plane but the frictional connection is such as to permit the platen carriage to be shifted vertically without lifting the roll support therewith.

More specifically, to the rear of the typewriter frame there are attached bracket members supporting a track upon which a wheeled truck or frame is guided in movement parallel to the path of movement of the platen carriage. On this truck are vertical pedestals or arms adapted to removably receive the roll of paper and from this truck extend flexible fingers which bear with slight friction against the opposite ends of the platen carriage so that as the platen carriage moves, the roll truck is moved also along its track. Because of the frictional engagement of the fingers with the ends of the platen carriage, however, the platen can move freely up and down without moving the roll support therewith and consequently the shift pressure is not appreciably increased.

It is apparent that the roll support should preferably be supported from the typewriter frame so that the whole assemblage will occupy the minimum of space. It is obvious that the roll support must not be carried by the platen carriage for that would increase the shift pressure too greatly. With most operators having an even touch, if they hit the key hard enough to shift both the platen carriage and the roll support, then they would hit the regular keys too hard. If they hit the regular keys with the proper force,

then they would be hitting the shift key with insufficient force. By having the roll support carried by means other than the platen carriage, this discrepancy is avoided. By 5 having the paper roll support close to the platen and moveable therewith, altho separately supported, the angle of the paper on the platen is kept steady, and consequently in proper alinement at all times as is highly 10 desirable. If the roll support did not move and were close to the typewriter, then this would cause the angle of the paper to change as the platen moved, and the writing would be out of alinement, whereas if the roll support were moved back a sufficient distance from the typewriter to avoid this change in angle of the paper, then the whole apparatus would take up entirely too much room and the device would be too clumsy. 15 20 Therefore, by having the attachment mounted on the frame of the typewriter, space is saved; by having it mounted separately from the platen carriage, the usual shift pressure is maintained; by having light frictional contact between the paper roll support and the platen carriage, joint horizontal movement of the platen carriage independent of the paper support is permitted. Thus the 25 30 paper is always kept in alinement and the operation of the typewriter is not otherwise modified. This attachment is especially for using rolls of checks made up for the expeditious preparation of pay-rolls and the like. 35 The invention is adapted for use with single copies or with multiple copies with intervening carbon paper employed as will be herein-after described.

Referring to the drawings, in which the 40 present preferred form of the invention is clearly set forth, it will be seen that to the rear of the typewriter frame 10 are attached two spaced bracket plates 11 and 12 having horizontal portions 13 and 14, supporting 45 spaced track bars 15 and 16. Pairs of wheels 17 and 18 are adapted to run along these track bars 15 and 16 and are mounted on the ends of shafts 19 and 20, fastened to the under side of a frame-plate 21 disposed above the 50 track bars 15 and 16 and having at its ends upright arms 22 and 23. Arm 23 is apertured to receive the end pin of a roll of paper 24, whereas arm 22 is provided in the usual manner with a slot 25 so that the other end pin 55 of the roll 24 can be slid into the slot 25 from the side and rest therein while the paper is being unrolled from the carrier.

The frame plate 21 has dependent ears 26 and 27 adjacent the pairs of wheels 17 and 60 18 which depend into and between the opening or channel formed between the track bars 15 and 16 to act as guides for the roll frame and to keep it in alined movement preferably parallel to the motion of the typewriter 65 platen carriage 28, on which is supported the

platen 29. A pair of flexible fingers 30 and 31 are fastened at one end to the ends of the frame plate arms 22 and 23 and extend forwardly to bear with light friction against the ends of the platen carriage 28. Preferably 70 felt or rubber pads 32 and 33 are disposed between the ends of the fingers 30 and 31 and the adjacent walls of the carriage.

It will be seen that horizontal movement of the platen carriage due to the operation of the 75 keys will cause the paper roll to travel therewith by reason of the flexible connecting fingers 30 and 31, but that when the shift key 34 is operated, the platen carriage will be lifted without lifting the paper roll 29 and 80 without increasing the shift pressure. Furthermore the weight of the paper roll and its support is taken entirely upon the track bars 15 and 16 and the friction of movement 85 of the paper roll and its support is very small. The paper 29 can be quickly lifted out of the arms 22 and 23, and that the entire frame plate 21 with the wheels 17 and 18 and fingers 30 and 31 can as readily be lifted away from the typewriter leaving 90 thereon, merely the bracket members 11 and 12.

It is understood that more than one roll can be supported back of the machine, for example, in Fig. 4 an extra roll 35 is shown 95 supported on the arms 22 and 23 and this can be employed when it is desired to make carbon copies. The carbon sheet can be inserted separately or carried on still another roll not shown. It will be also understood that the 100 roll support instead of being arranged to rest on the track bars 15 and 16, may be in any suitable manner, hung or suspended from a track of the same general type which is fastened to the back of the machine. 105

The device is therefore simple, compact, easily applied to and removed from the typewriter and works therewith without in any serious manner disturbing the normal working of the typewriter mechanism itself. 110

While I have described my improvement in detail and with respect to a preferred form thereof, I do not desire to be limited to such details or form since many changes and modifications may be made and the invention embodied in other forms without departing from the spirit and scope of the invention in its broader aspects. Hence I desire to cover all modifications and forms coming within the language or scope of any one or 115 more of the appended claims. 120

What I claim as new and desire to secure by Letters Patent, is:

1. In combination with a typewriter having a platen carriage and a platen shift frame 125 therein, a paper roll, a support for said roll independent of the carriage, means for moving the roll along the support, and flexible connections from the roll-support and frictionally bearing against the ends of the platen 130

shift frame to cause their joint movement in a horizontal plane.

2. In combination with a typewriter having a platen carriage and a platen shift frame therein, a paper roll a support for said roll independent of the carriage, means for moving the roll along the support, and flexible fingers extending from the roll-support and frictionally bearing against the ends of the platen shift frame to cause their joint movement in a horizontal plane and permitting the independent vertical movement of the platen shift frame.

3. In combination with a typewriter having a platen carriage and a platen shift frame therein, a track supported from the frame of the typewriter, a roll-frame adapted to be supported on said track, means on said frame and engaging said track to guide the frame thereon in a predetermined direction, and flexible fingers extending from the frame and bearing frictionally against the ends of the platen shift frame to cause their joint movement in one plane and permitting the independent movement of the platen shift frame in another plane.

4. In combination with a typewriter having a platen carriage, a slotted track supported from the frame of the typewriter, a roll-frame adapted to be supported on said track, ears on said frame extending into said slot to guide the frame along the track in a predetermined direction, and means connecting the frame with the carriage to cause their joint movement in one plane.

5. In combination with a typewriter having a platen carriage, a slotted track supported from the frame of the typewriter, a roll-frame adapted to be supported on said track, ears on said frame extending into said slot to guide the frame along the track in a predetermined direction, and means connecting the frame with the carriage to cause their joint movement in one plane and permitting the independent movement of the carriage in another plane.

6. In combination with a typewriter having a platen carriage, a slotted track supported from the frame of the typewriter, a roll-frame adapted to be supported on said track, ears on said frame and extending into said slot to guide the frame along the track in a predetermined direction, and fingers on said frame extending to and frictionally bearing against the ends of the platen carriage to cause their joint movement in a horizontal plane and permitting the independent movement in a vertical plane of the platen carriage.

7. In combination with a typewriter having a platen carriage, a slotted track supported from the frame of the typewriter, a roll-frame adapted to be supported on said track, ears on said roll-frame and extending into said slot to guide the roll-frame along

the track in a predetermined direction, fingers on said roll-frame extending to and frictionally bearing against the ends of the platen carriage to cause the joint movement of the frame and the carriage in a horizontal plane and permitting the independent movement in a vertical plane of the platen carriage, and flexible pads disposed between the ends of the fingers and the platen carriage.

In testimony that I claim the invention set forth, I affix my signature hereto.

HENRY J. TYNAN.
